UNITED STATES PATENT OFFICE.

SAMUEL D. PAGE, OF DES MOINES, IOWA.

TEMPORARY BINDER.

1,201,088.

Specification of Letters Patent. Patented Oct. 10, 1916.

Application filed October 14, 1915. Serial No. 55,748.

To all whom it may concern:

Be it known that I, SAMUEL D. PAGE, a citizen of the United States, residing at Des Moines, in the county of Polk and State of Iowa, have invented certain new and useful Improvements in Temporary Binders, of which the following is a specification.

This invention relates to improvements in temporary binders, particularly adapted, though not necessarily limited in its use for temporarily binding together a number of periodicals such as newspapers, magazines and the like, into a compact cover or casing and one of the objects of the same is to improve and simplify devices of this character and to provide an improved device whereby the articles may be readily inserted and removed when desired.

Other and further objects will appear from the following specification and claims taken in connection with the accompanying drawing and in which;

Figure 1 is a perspective view of an improved device of this character, showing the same open and with several periodicals secured therein. Fig. 2 is a detail perspective view of a modified form of the invention which is adapted for use when longer articles are to be bound therein. Fig. 3 is a detail sectional view taken on line 3—3, Fig. 1. Fig. 4 is a longitudinal sectional view on line 4—4, Fig. 1. Fig. 5 is a longitudinal sectional view, taken on line 5—5, Fig. 2.

Referring more particularly to the drawing, the numeral 10 designates a cover or casing of any desired size and configuration and constructed of any suitable material. To the back 11 of this casing is secured a body portion 12, constructed of any suitable stiff material such as metal or the like and the extremities 13 of this body portion are deflected as shown, to form laterally projecting flanges within each of which flanges are arranged apertures or openings 14 passing therethrough and these openings are preferably elongated in directions transverse with respect to the body 12. The body portion 12 is preferably of a length substantially equal to the back 11 and is secured in position in any suitable manner.

The periodicals 16 are placed in the binder in an open position as shown in Fig. 1 so that the edges thereof will stand between the flanges 13. Fastening devices 17 preferably in the form of wires are provided which pass over the periodicals and the ends

thereof pass through the apertures 14 in the flanges 13. The extremities 18 of the fastening wires are bent back upon themselves and over the respective flanges 13 so as to 60 secure the parts together.

In use, one of the ends of the fastening wire is preferably in the form of a hook, while the other end is straight so as to facilitate the insertion of the fastening wires. 65 After they are placed in position, the straight end of the wire is bent back as heretofore described. The body 12 may be of any desired width according to the size of the casing and if it is desired to bind together periodicals of considerable length or size, one or more additional portions 19 may be provided, each of which is provided with a laterally projecting flange 20, having openings 21 therethrough, similar to the openings 14 in the flanges 13. The body of the portion 19 is connected with the body portion 12 and can be arranged at any point intermediate the ends of the latter, so that the openings 21 therein will be in alinement 70 with the openings 14. 75

In the event of the use of the portion 19 it is obvious that the periodicals must be provided with an opening through which this portion 20 passes to permit the fastening wires 17 to pass therethrough. The elongated openings 14 permit a plurality of periodicals to be held together. 85

With this improved construction it will be manifest that the periodicals may be 90 readily inserted in the casing or removed when desired.

What is claimed as new is:

1. A temporary binder embodying a body portion, the extremities of said body being shaped to form laterally projecting spaced substantially parallel flanges, there being openings in the flanges, and a fastening wire extending lengthwise of said body, the extremities of the wire projecting through the 100 openings and being bent back over the flanges and upon itself. 95

2. A temporary binder embodying a body portion, said body being provided with a plurality of laterally projecting flanges spaced lengthwise of the body, each of said flanges being provided with an elongated opening extending transversely with respect to the said body, and detachable securing wires extending lengthwise of the body and 110 passing through the said openings, the extremities of the wires being bent back upon

themselves and over the respective adjacent flanges.

3. A temporary binder embodying a body portion, substantially parallel laterally projecting portions spaced longitudinally of said body, said portions being each provided with a plurality of separated openings therethrough, said openings being elongated transversely of the said body, and the respective openings in the said portions being in alinement, and fastening wires passing

through alined openings, the ends of the wires being bent back upon themselves and over the respective adjacent laterally projecting portion.

In witness whereof, I hereunto subscribe my name to this specification in the presence of two witnesses.

15 SAMUEL D. PAGE.
